DESIGN FOR A BRIDGE FOR AN
OPHTHALMIC MOUNTING

Henry J. Langknecht, Rochester, N. Y., assignor
to Shuron Optical Company, Inc., Geneva, N. Y.,
a corporation of New York

Application July 24, 1941, Serial No. 102,448

Term of patent 14 years

To all whom it may concern:

Be it known that I, Henry J. Langknecht, a citizen of the United States, residing in Rochester, county of Monroe, and State of New York, have invented a new, original, and ornamental Design for a Bridge for an Ophthalmic Mounting, of which the following is a specification, reference being had to the accompanying drawing, forming part thereof.

In the drawing:

Figure 1 is a front elevation of a bridge for an ophthalmic mounting showing my new design;

Figure 2 is a top plan view of the bridge shown in Figure 1.

The present design embodies as its characteristic feature a crest made in the shape of a "W," the ends of the crest being affixed to the backs of the flat side pieces.

I claim:

The ornamental design for a bridge for an ophthalmic mounting, substantially as shown and described.

HENRY J. LANGKNECHT.
